UNITED STATES PATENT OFFICE.

JOHN P. CARMICHAEL, OF MILWAUKEE, WISCONSIN.

TOOTHPICK.

Application filed January 11, 1922. Serial No. 528,506.

To all whom it may concern:

Be it known that I, JOHN P. CARMICHAEL, a citizen of the United States, residing at Milwaukee, county of Milwaukee, and State 5 of Wisconsin, have invented new and useful Improvements in Toothpicks, of which the following is a specification.

My invention relates to improvements in tooth picks.

10 The objects of my invention are to provide a form of tooth pick, which is adapted particularly to be used as a probe between the gums and teeth, and between the root portions of adjoining teeth without injury to 15 the surfaces with which it contacts, but in a manner to effectually remove foreign matter; to provide a form of tooth pick which will medicate the surfaces to which it is applied; which will not wound or introduce 20 fragments or slivers into the delicate gum tissues; which will be extremely flexible at this point, and sufficiently rigid otherwise to promote effective manipulation.

A further object is to provide tooth picks 25 which will be of uniform quality and flexibility; and which may be used as an effective brush between the gums and teeth.

In the drawings:—

Figure 1 illustrates one embodiment of my 30 invention on an enlarged scale, with one end portion broken away obliquely to show the interior structure.

Figure 2 is a similar view showing a modification.

35 Figure 3 is a view showing a tooth pick package adapted to be marketed as a new article of manufacture.

Figure 4 shows a further modification.

Figure 5 illustrates the pick in use.

40 The improved tooth pick has a longitudinally extending central core piece composed of fibrous material 1, having a reinforcing covering or binder 2, and progressively thickening from the point 3 toward the 45 central portion. The covering 2 may be composed of any suitable composition such as paraffin, celluloid or rubber impregnated with a medicament or antiseptic material near the point, or near both ends if pointed 50 at both ends.

The fibrous core piece is preferably artificially formed and composed of a flattened bundle of fibers, connected with each other by the binder to form an integral unit. The 55 binding material may extend to the extreme point as shown in Figure 1, or it may ter-

minate near the point leaving the fibers exposed as shown at 3^a in Figure 2. If exposed, the binder will extend closely enough to the point to hold the fibers from spreading to any great extent, and to keep them from breaking away. The tips may separate slightly however, and are adapted to brush out foreign matter from between the teeth and gums when the pick is manipulated with a sweeping motion along the surfaces to be cleaned.

The bundle of fibers being preferably flattened and tapered at the point 3, and being reinforced as above described, it becomes 70 possible to provide a point of extreme thinness and flexibility, which will not break or disintegrate under proper usage, but which will follow the contour of a tooth root or enter crevices in or between teeth, and be 75 guided even by delicate tissue without tearing, wounding or penetrating such tissue.

Where the character or quality of the reinforcing or binder composition is such as to prevent it from properly distributing 80 the antiseptic material or medicament, such material may be applied as a coating directly to the fibers, or as indicated in Figure 1, it may be applied to an intermediate cellulose binder which connects the fibers with 85 each other, and which in turn is reinforced by a covering of rubber or celluloid along the central portion or shank portion of the pick.

The improved picks are peculiarly adapted 90 to be assembled in a package, wherein the shanks are bound in parallel relation to each other by a connecting back or bar 4, from which the picks may be torn individually when required for use. The bar may be secured to, or between, a set of covers 5 which 95 protects the picks, and keeps them in a sanitary condition.

While the device is referred to as a tooth pick, its function more nearly resembles 100 that of a probe, the purpose of which is to push infectious matter from between the gums and the root of a tooth without promoting infection by tearing delicate tissues. The point of the pick being extremely 105 flexible and soft at the tip, it may be guided by the tissues along a circular path around the tooth, as illustrated in Figure 5, the upwardly projecting gum or portion 6 between the tooth shanks being utilized to 110 cause flexion of the point 3.

It is not material whether the core piece

be formed of fibrous material as shown in Figure 1, or whether a re-enforcing central core piece 7 be covered with fibrous material 1^b as shown in Figure 4, these two forms of construction being regarded as substantial equivalents for each other.

I claim:—

1. A tooth pick composed of parallel fibers having a thin, flat, flexible end portion 10 tapering on all sides toward a point, said fibers being held together by a cellulose binder, which with the fibers has sufficient flexibility to follow the surfaces of the tooth root and to be guided by the gums into crevices 15 between teeth without breaking, said tooth pick having its shank portion reenforced by more rigid material.
2. A tooth pick having a non-breakable fibrous point and having a non-irritating 20 covering and tapering from all sides toward the point, said fibers being bound together along the tapering portion of the tooth pick into close proximity to the point to prevent the fibers from diverging in any direction 25 under normal conditions.
3. A tooth pick having a flexible non-

breakable fibrous point, and a reinforced shank composed of material which is more rigid than the material of which the point is composed.

4. A tooth pick having a point portion composed of medicated parallel fibers, connected with each other in the shank portion by a suitable binder, the point portion being flexible, and tapered on all sides to the ex- 35 tremity.

5. A tooth pick composed of non-breakable fibers permanently reinforced and stiffened by embedding material and connected with each other in the shank portion, and 40 having converging exposed projecting ends forming the point of the pick, and adapted to serve as a brush.

6. A tooth pick composed of a flattened and tapered bundle of non-breakable fibers, 45 in combination with an artificial embedding material connecting the fibers in the shank portions, and a reinforcing covering progressively increasing in thickness from its ends to the central portion.

JOHN P. CARMICHAEL.
